(74) *Attorney, Agent, or Firm* — Emmanuel Coffy, Esq.

(57) **CLAIM**

The ornamental design for a sock, as shown and described.

DESCRIPTION

This application claims the benefit to U.S. non-Provisional application Ser. No. 16/677,465 filed on Nov. 7, 2019, which application is incorporated herein by reference as if herein set forth in its entirety.

FIG. 1 is a front perspective view of a first embodiment of a sock showing the claimed design;

FIG. 2 is a back perspective view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof;

FIG. 9 is a front perspective view of a second embodiment of a sock showing the claimed design;

FIG. 10 is a back perspective view thereof;

FIG. 11 is a front view thereof;

FIG. 12 is a back view thereof;

FIG. 13 is a right side view thereof;

FIG. 14 is a left side view thereof;

FIG. 15 is a top view thereof;

FIG. 16 is a bottom view thereof;

FIG. 17 is a front right side perspective view of a third embodiment of a sock showing the claimed design;

FIG. 18 is a back left side perspective view thereof;

FIG. 19 is a bottom right side perspective view thereof; and,

FIG. 20 is a right side view thereof.

The broken lines in the figures are for the purpose of illustrating stitching and environment only and form no part of the claimed design.

1 Claim, 18 Drawing Sheets
